CONCEALED HINGE FOR AUTOMOBILE AND
OTHER DOORS

Paul Etzel, Buffalo, N. Y.

Application May 11, 1933, Serial No. 670,561

2 Claims. (Cl. 296—44)

This invention relates to hinges for automobile and other doors and particularly to the so-called concealed hinges therefor.

The general object of this invention is to provide a hinge which is entirely concealed and yet which is strong and serviceable and which provides for secure attachment of the door to the hinge and of the hinge to the body pillar, and a further object is to provide a hinge particularly adapted to be used with car bodies having a considerable turnunder sweep and which is so constructed as to allow the door to swing far enough out but entirely clear the body and any ornamental beading thereon.

Other objects will appear in the course of the following description.

My invention is illustrated in the accompanying drawing, wherein:

Figure 1 is a horizontal section through the body pillar and door pillar of a car showing my hinge applied thereto, the figure showing in dotted lines the door swung to its open position;

Figure 2 is a vertical section on the line 2—2 of Figure 1;

Figure 3 is a vertical section on the line 3—3 of Figure 2.

Referring to the drawing, A designates the body pillar of the car and B the door pillar. The body pillar A is provided with a front transverse face a^2 and the door pillar B is provided with a front transverse face b^2 which opposes the front face a^2 of the body pillar, as shown in Fig. 2. The body pillar is deeply recessed or cut away in the front transverse face thereof at the point where the hinge is to be applied as at a and the confronting front transverse face of the door pillar is deeply recessed or cut away at b . Disposed within the cut-away portion a of the body pillar are the two angular supporting plates 10 and 11 which form a stationary hinge leaf and which are disposed in shallow recesses a' in the face of the door pillar above and below the deep recess a therein. Each of these plates has a horizontal extension 12, these extensions extending into the recess a and these extensions are connected by a pintle 13 arranged adjacent to the outer longitudinal surface of the body. The plates 10 and 11 are held to the body pillar A by means of screws 14. The pintle 13 may be made in one piece with the plate extensions 12 or may be driven into these extensions.

Disposed between the extensions 12 is a hinge arm 15 which at one end is formed with the elongated eye or sleeve 16 which surrounds the

pintle 13 and rotates thereon. This eye is slightly longer than the arm 15 as shown clearly in Figure 2 so as to reduce friction. The recess a is so formed that the arm 15 fits snugly in this recess as shown in Figure 1 and bears against the end and bottom wall of the recess when the door is closed thus limiting the closing movement of the door. The member 15 at its free end is angularly extended at 17 and this angular extension 17 is bifurcated, that is recessed at 18 at its middle. The portion 17 at its outer end is flat and wide as shown in Figure 1. The door B has a shallow recess at b' on the inner side of the deep recess b for the reception of an elongated plate, hinge leaf or hinge element 19 which is attached to the door pillar by the screws 20 and which at its middle is formed with an outwardly projecting lug 21 which fits within the recess 18 and bears flat against the inner wall of the recess.

It will be noted that the end face of the angular portion 17 of element 15 fits flat against the outer face of the plate 19 and that the lug 21 has an angular face shown in dotted lines in Figure 1 which fits flat against the vertical face 23 of the recess 18. A screw or pin 22 extends downward through the angular extremity 17 and intersects the recess 18 and passes through the lug 21. Because of the flat contacting faces between the plate 19 and the ends of the angular portion 17, there is no turning movement of the plate 19 with relation to the element 15 but these two elements 19 and 15 are held rigidly engaged with each other by the pin 22.

Attached to the face of the body pillar A, is a metallic cover or plate 23 which extends over the sleeve 16 and over the recess a and beyond this recess and is then bent inward at 24 over a strip 25 on the body so that this projecting portion of the plate 23 extends partially over the recess b in the door pillar. The door pillar is also provided on its face with the cover or plate 26 which is extended partially over the recess b and then returned upon itself over the strip 27 on the door as at 28. Thus when the door is closed, the front edges of the cover plates 23 and 26 are opposed and close together and offset forwardly from the joint between the body and door pillars whereby the joint between the door and the body is practically closed and is practically unobservable while the hinge elements are entirely enclosed and invisible. This offsetting of the joint between the plates 23 and 26 is preferably effected by extending the body cover or plate 23 beyond the front transverse

face of the body pillar A and terminating the front edge of the door cover or plate 26 short of the front transverse face of the door pillar B, as shown in Fig. 1.

5 Today with enclosed cars, the car door and the body are ordinarily formed with an outwardly projecting molding or bead which is designated C in Figure 1 whereby a turn-under sweep is produced on the lower part of the body relative to 10 the upper part thereof. This renders it impossible to use the ordinary or concealed hinge because the door cannot open far enough before it strikes this molding C. My improved hinge is 15 designed to overcome this difficulty as shown in Figure 1 which illustrates the fact that the door may be swung farther outwardly away from the body and opened fully or to the dotted lined position before the molding or bead on the door will strike the molding or bead C on the body. Thus 20 my hinge can be used for enclosed cars because it is constructed to permit the door to open far enough to clear the widest point above the body at the belt molding.

Of course, it will be understood that two or 25 more of these hinges are to be used on each door and it will be seen that my improved hinge is heavy enough to carry the enclosed body door and that it allows the door to swing far enough out to clear the body.

30 By providing the body pillar with a deep recess a for the reception of the angular extension or arm 15, 17 when the hinge is closed and a deep recess b in the door pillar, it is possible to open 35 the door fully and clear the laterally projecting swell or salient part C of the body which is formed thereon by the molding above the lower turn-under. Upon opening the door the recess b in the door pillar receives the outer front corner of the respective body pillar, as clearly shown 40 by dotted lines in Fig. 1.

This construction also permits the recess a of 45 the body pillar and the recess b of the door pillar to be concealed by the covers 23, 28 and permits the meeting edges of these covers to be located 50 on one side or offset outwardly or forwardly from the joint between the body and door pillars and thus effectively close this last-mentioned joint while at the same time fully concealing the hinge when the door is closed and still permitting 55 the door to be opened fully inasmuch as the door pillar recess b at this time not only receives that portion of the body adjacent to the outer front corner of the body pillar but also the outer edge portion of the body pillar adjacent to the turn 24 of this cover.

The form of this hinge and the manner of mounting the same therefore permits of completely concealing the hinge and enables the door to clear the laterally projecting swell on the body

and swing into a fully opened position and also permits of reducing the gap between the outer hinge covers to a minimum and thus preserve an attractive appearance of the body and door when closed.

5 While I have illustrated a certain detailed construction and form for this hinge, I do not wish to be limited thereto except as defined in the appended claims.

It will be noticed that one of the advantages of 10 this construction lies in the fact that the member 19 which is attached to the door or door post is detachable from the hinge element 17 so that if the door has to be taken off the body, this can be accomplished by simply removing the bolt or 15 screw 22 and pulling the door away from the remainder of the hinge. Thus the hinge may be removed from the door without scratching the pane or removing the trimming on the door or body or removing any of the attaching screws. 20

I claim:—

1. A hinge mounting for automobile and other doors comprising a body pillar provided in its front transverse face with a recess, a door pillar 25 provided in its transverse front face with a recess adjacent to its outer front corner and an elevation adjacent to its inner front corner, and a hinge including a body leaf secured to the body pillar, a door leaf secured to said elevation of the door pillar, an arm projecting from said door leaf 30 into the recess of the body pillar, and a pintle arranged in the recess of the body pillar adjacent to the outer front corner thereof and pivotally connecting the body hinge leaf and said arm, said pillar recess being adapted to receive the outer 35 front corner of said body pillar upon turning the door into its open position.

2. A hinge mounting for automobile and other doors comprising a body pillar provided in its front transverse face with a recess, a door pillar 40 provided in its transverse front face with a recess adjacent to its outer front corner and an elevation adjacent to its inner front corner, a hinge including a body leaf secured to the body pillar, a door leaf secured to said elevation of the door 45 pillar, an arm projecting from said door leaf into the recess of the body pillar, and a pintle arranged in the recess of the body pillar adjacent to the outer front corner thereof and pivotally connecting the body hinge leaf and said arm; a 50 body flange projecting forwardly from the outer front corner of the body pillar beyond the front face thereof, and a door flange projecting from the outer front corner of said door pillar and terminating short of the front face thereof and 55 adapted to oppose the body flange in the closed position of the door.

PAUL ETZEL.
